UNITED STATES PATENT OFFICE.

LOUIS SCHMEISSER, OF ERFURT, GERMANY.

AUTOMATIC FIREARM.

1,077,760.

Specification of Letters Patent.

Patented Nov. 4, 1913.

Application filed March 17, 1913. Serial No. 754,958.

To all whom it may concern:

Be it known that I, LOUIS SCHMEISSER, a subject of the German Emperor, and resident of Erfurt, Germany, have invented certain new and useful Improvements in Automatic Firearms, of which the following is a specification.

This invention relates to an automatic fire-arm with fixed barrel and with a rectilinearly moving breech mechanism opened through the recoil of the fire arm by a movable butt-cap, this breech mechanism being characterized in that on the one hand a tenon of the connecting device between the butt-cap and the breech block engages a depression provided with an incline of the breech block for the purpose of automatically unlocking this breech block and moving it backward, while on the other hand the breech block carries an oscillating spring controlled locking lever which causes the breech block to swing into the locking position.

The accompanying drawings, given by way of example, show one form of embodiment of the invention and in this drawing:

Figure 1 shows the central part of the fire-arm, the side-wall being removed. Fig. 2 is a vertical longitudinal section of the rear part of the butt-end of the stock; Fig. 3 is a horizontal longitudinal section of the breech mechanism, the knob of the manipulating handle being broken off. Fig. 4 is an elevation view of the breech block taken from the right hand side. Fig. 5 is an elevation view of the same part but in the position it assumes when the manipulating knob has been moved back. Fig. 6 is a sectional view on line *e-f* of Fig. 4.

The breech casing 1 which is open at the top is closed by a top or lid 9 which toward the rear end bears against the rear wall of the casing 1 and is rigidly connected therewith by means of a bolt 10. The breech block 3 having a rectangle shaped cross section is mounted in the casing 1 so as to be adapted to slide longitudinally therein. This breech block 3 is locked in the well known manner by being able to oscillate in a corresponding manner around its front end and by bearing with its rear end 3^a against the step shaped extension 9^a of the top or lid 9 (Fig. 1).

The handle knob bar 6 (Fig. 3) which is driven by a spring 7 is mounted in the breech block 3 so as to be able to be longitudi-

nally moved therein. The handle knob bar 6 and the spring 7 are held in the breech block 3 by the firing pin 4 which passes through them (Fig. 3). The breech block 3 carries at its rear end the locking lever 8 which is fulcrumed on the pivot 8^c. A tenon 4^a which is positioned at the rear end of the firing pin 4 and engages the said locking lever 8, holds the firing pin 4 securely in the breech block 3 (Fig. 3).

As seen from Figs. 4 and 5, the rear end of the handle knob bar 6 is connected with the locking lever 8 in such a manner, that when the bar 6 is moved backward, the end 8^a of the lever 8 moves upward in the position shown by Fig. 5. When the handle knob bar is moved forward, the tooth 6^a provided at its rear end pulls, by acting upon the tooth 8^b of the closing lever 8, the end 8^a of the latter downward in the position shown by Fig. 4. The parts contained in the breech block 3 work therefor in the following manner: When the handle knob bar 6 is moved backward, *i. e.* from the position shown by Fig. 4 into the position shown by Fig. 5, its rear end by striking against the locking lever 8 brings the latter from the position shown by Fig. 4 into the one shown by Fig. 5. Thus the rear end of the breech block 3 is moved downward and is thus unlocked in the following manner: When the member 8^a is in the position shown by Fig. 5, the breech block 3 drops a slight degree until the shoulder 9^a is freed from its locking notch and allows the block to slide backward in the casing 1. When the handle knob bar 6 is again moved forward its tooth 6^a provided at its rear end engages the tooth 8^b of the locking lever 8 and pulls the latter in the position shown by Fig. 4, whereafter the rear end of the breech block is tilted upward into the locking position. However, the handle knob bar 6 is already pushed forward by the driving spring 7 and thus the locking lever 8 is started on its closing movement. The incline 8^c of the locking lever forces the firing pin 4 backward by means of the tenon 4^a when the breech mechanism is opened (Figs. 4 and 5).

Mounted on the rear end of the stock is a butt-cap 16 guided in a suitable manner so as to be able to move in a longitudinal direction, this butt-cap being connected by means of intermediate members 19, 18 with a trunnional rod 20 adapted to be longitudinally

shifted in a bore of the butt end of the stock. The butt-cap 16 is acted upon in the well known manner by a pressure spring 21. The front end of the fractional rod 20 is connected by means of a chain link 22 with the oscillating lever 23 which engages a slide 24 mounted in a sliding manner in a longitudinal groove of the breech casing and carries at its front end a tenon 24^a. The latter 5 passes through the casing 1 and engages a longitudinal groove 3^b of the breech block 3 (Figs. 1, 6). The groove 3^b of the breech block 3 terminates at its rear end in an incline 3^c. When the butt-cap is pressed by a 10 steady push into the butt-end of the stock until it reaches its extreme position, against the action of the spring 21, the fractional rod 20 and the parts 22, 23, 24 connected therewith, are moved backward and by this backward 15 motion the breech block 3 which had been pressed upward into the locking position, and held in this position by the end 8^a of the locking lever 8, is caused to be pushed by the receding tenon 24^a which slides downwardly and rearwardly on the incline 3^c, and over-rides said incline, thus pressing the breech block downward against the action 20 of the spring 7, until the shoulder of the breech block slips by the step 9^a, and away 25 from the locked position and is moved backward half of the length of its backward stroke against the action of the main spring not shown in the drawings. However, when the motion of the butt-cap is brought about 30 by the recoil of the fire-arm against the shoulder of the marksman, the backward motion of the parts 20, 22, 23, 24 also takes place so violently that the oscillating lever 23 performs a jerky motion so that the 35 breech block is thrown backward in the casing entirely into its rearmost position against the action of the main spring. During this complete backward motion of the breech block, the breech mechanism has again 40 been cocked, the case of the fired cartridge has been ejected; the breech block thereafter has been forced again forward into the closing position and during this motion a fresh cartridge has been conveyed from the magazine into the barrel. The locking of the 45 mechanism then again takes place, owing to the driving spring 7 forcing the handle knob bar 6 again forward and owing to its tooth 6^a moving the locking lever 8 by means 50 of its tooth 8^b in such a manner that the end 8^a of the locking lever which bears downward against the casing 1 forces the breech

block upward into the locking position (Fig. 1) whereby the closing of the mechanism of the fire-arm has been completed. It is seen that thus the fire-arm has been automatically loaded and is again ready for firing.

Having now fully described my said invention, what I claim and desire to secure by Letters Patent, is:

1. In an automatic fire-arm of the kind described, the combination with the fixed barrel, the stock, the breech casing and the breech block of a butt-cap, means for mounting the said butt-cap in a movable manner on the butt end of the stock, a spring controlling said butt cap, connecting means for connecting said butt-cap with said breech block, a groove in said breech block, an incline in said opening, a tenon provided on said connecting means and adapted to engage the said incline for the purpose of automatically unlocking the said breech block, a locking lever fulcrumed on the said breech block, a spring controlling said locking lever which locking lever is adapted to cause the said breech block to oscillate into the locking position, substantially as and for the purpose set forth.

2. In an automatic fire-arm of the kind described the combination with the fixed barrel, the breech casing and the breech block of a locking lever, a hook on said locking lever, a handle knob, a bar connected with said handle knob and adapted to longitudinally slide in said breech block, a spring adapted to control said bar and a hook provided on said bar and adapted to engage the hook of said locking lever, substantially as and for the purpose set forth.

3. In an automatic fire-arm of the kind described, the combination with the fixed barrel, the breech casing and the breech block, a locking lever fulcrumed on said breech block, a handle knob bar adapted to slide longitudinally in said breech block, a firing pin housed in said breech block and adapted to hold the said bar in position, a spring slid on said firing pin, and a tenon provided on said firing pin and adapted to engage the said locking lever substantially as and for the purpose set forth.

In testimony whereof I have hereunto set my hand in presence of two witnesses.

LOUIS SCHMEISSER.
